UNITED STATES PATENT OFFICE

2,603,033

RETRACTABLE LANDING GEAR FOR
TOY AIRPLANES

Harold H. Sharp, La Porte, Tex.

Application July 11, 1947, Serial No. 760,415

5 Claims. (Cl. 46—77)

1

The invention relates to a landing gear mechanism for toy airplanes.

It is customary in flying toy or model airplanes in present day practice to provide a skid which fits under the plane as it travels along the ground prior to take off. When the plane attains the proper speed for take off, it rises from the skid and ascends into the air.

This procedure is followed, particularly where it is desirable to obtain a maximum speed with the plane while it is in flight. With no projecting wheel structure and landing gear mechanism, wind resistance is lessened, which tends to increase the speed of the plane and the ease of control of the performance of the plane.

A difficulty with this mode of operation, however, resides in the fact that when the operator of the model plane desires to bring the plane in, it is necessary that the plane make a belly landing.

The present invention is directed to the landing gear mechanism, which is controlled by the manipulation of the elevator controls which are used to control the flight of the plane.

An object of the present invention is to provide a landing gear which is operable to retract wheels in flight and operable to lower the wheels before landing.

Another object of the invention is to provide a landing gear mechanism, which mechanism is operable at will by the operator to raise and lower the wheels of a toy airplane.

Still another object of the invention is to provide a construction which is positive in its action, yet simple in operation.

A further object of the invention is to provide in a toy airplane a landing gear mechanism which is easily manufactured, of simple construction, but which is durable.

A still further object of the invention is to provide a landing gear mechanism for a toy airplane which mechanism has a minimum of moving parts and which is relatively easy to install in the model airplane.

A further object of the invention is to provide a landing gear for model airplanes which is operable by the elevator controls which control the flight of the plane, the mechanism being operable during flight of the airplane or at any time the operator so desires.

Other and further objects and advantages of the invention will become readily apparent from the consideration of the following description and drawings, wherein:

Fig. 1 is a top plan view showing the preferred

2

embodiment of the landing gear mechanism and its relationship when the wheels are retracted.

Fig. 2 is a front elevation of the construction and its relationship when the wheels are lowered.

Fig. 3 is a modified form of a construction shown in Fig. 1.

Fig. 4 is an enlarged view to more clearly illustrate the construction of the mechanism.

In Fig. 1 the mechanism is shown generally at 10. 2. A rubber band 3 is secured to the end 4 of a crank 5 which crank is rotatably mounted at 6 in a beam 7 of the airplane. The crank 5 is connected to a rock lever 8 by means of the link 9 secured at 10 on the crank end of the crank 5 and at 12 in the eye 13 of the rock lever 8. The rock lever 8 is pivotally secured at 14. The rock lever 8 is connected to the wheel assemblies 16 which comprise the rods 15, the crank heads 17, which heads rotate the rods 18 to move a wheel support 19 and wheels 20.

A stop rest or bell lever 20' pivotally mounted at 22 adjacent a crank end 10' of the crank 5 is provided with an eye 21 to which the elevator controls 23 and 24 are secured. Elevator controls

25 23 and 24 are control lines leading to the ground and their direction is changed by means (not shown), so that they extend laterally from the plane. For the purposes of this description control line 23 may be designated the "up" control line and control line 24 as the "down" control line. Normally the crank end 10' of the crank 5 will be in engagement with the stop rest 20'. The latter will have connecting means (not shown) extending to conventional elevators. In

35 normal operation of the plane this will be a sliding engagement. However, by moving the stop rest 20' by means of the elevator controls 23 and 24 beyond a predetermined position, the crank end 10' of the crank 5 may be disengaged from

40 such rest so that it rotates through 180° and contacts the other side and end of the stop rest 20'. As the crank end 10' moves through this arc of 180° the link 9 is moved, thereby pivoting the rock lever 8 which in turn moves the rod 15, the 45 crank ends 17 and the wheels 20, whereby the wheels will be moved to or from retracted position.

It seems obvious that so long as tension remains in the rubber band or other mechanism which 50 tends to rotate the crank 5, the wheels may be retracted or lowered any number of times.

Fig. 3 shows an alternate construction wherein a spring 30 is secured at 31 to the rock lever 8 and at 32 to support structure in the airplane 55 which spring is used in cases where the wheels

of the airplane are unusually heavy. That is to say, the ordinary action of the landing gear mechanism might not be strong enough to raise heavy wheels once they are lowered. Therefore, the spring 30, which is positioned so that it normally tends to retain the wheels in retracted position is provided so that when the mechanism is actuated to raise the wheels, additional support will be obtained from the spring.

While the operation of the invention seems apparent from the foregoing, by way of a summary and further explanation, it will be assumed that the airplane is traveling along the ground prior to take off. When the plane reaches the desired speed for take off, the operator will give a hard "down" pull on one of the control strings. This hard "down" movement of the control string disengages the end 10 of the crank 5 from the stop rest or bell lever 20 and the rubber band causes the crank to rotate, actuating the mechanism so that the wheels are retracted.

If for any reason it is desired to lower the wheels, it is only necessary for the operator to give a hard "up" pull on the elevator control string which manipulates the elevators of the airplane to cause it to descend. When this is done, the stop rest 20 is moved angularly in the opposite direction so that the crank end 10 again disengages from the stop rest 20 and rotates another 180°. This actuates the rods 15 to lower the wheels to a landing position.

While the foregoing has referred to a hard "down" and "up" for retraction and lowering the landing gear respectively, it is of course apparent that the control string movement could be reversed although that described is deemed preferable. Reverse control could readily be obtained by reversing the pivot connection of the rods 15 to the rock lever 8.

A lever 35 is provided, extending rearwardly to control a tail wheel if one is used, or it may be hooked up to a throttle control and to control the flaps if so desired.

A construction in accordance with this invention is not limited in its operation by the speed of the airplane, nor is it necessary that an additional string be used to control the mechanism. The two elevator wires that are used to control the flight of the plane serve as a means by which the mechanism is actuated to either retract or lower the wheels.

Broadly the invention contemplates a landing gear mechanism for model airplanes, which mechanism is operable at will by the operator by manipulation of the elevator controls.

The invention claimed is:

1. A retractable landing gear mechanism for toy airplanes operable by control lines, comprising, a crank rotatably mounted in the plane, means connected therewith tending to rotate said crank, a rock lever pivotally mounted in the plane, a link connecting said crank and said lever, rods connected to said lever and extending laterally thereof, crank head ends connected to the ends of said rods, wheel supports connected to said crankheads, wheels mounted on said supports, a bell lever pivotally mounted adjacent the crank end of said crank, said control lines being operatively connected to said bell lever, said bell lever being normally engaged with said crank but movable by the control lines whereby said crank rotating means rotates said crank through 180° whereby said link pivots said rock lever to move said laterally extending rods to raise and lower said wheels.

2. A landing gear mechanism for toy airplanes operable by control lines to raise and lower the wheels at will, comprising, a crank rotatably mounted in said airplane, means to rotate said 5 crank, a rock lever pivotally mounted in said plane and linked with said crank, rods extending laterally from said rock lever, wheel supports connected on the ends of said rods, a bell lever pivotally mounted adjacent said crank and normally engaged therewith, said control lines being operatively connected to said bell lever, said bell lever being movable by the control lines to disengage it from said crank whereby said means 10 rotates said crank through substantially 180° to raise and lower said wheels.

3. A landing gear mechanism for toy airplanes operable by control lines to raise and lower the wheels of the airplane at will, comprising, a crank rotatably mounted in said plane, means to rotate 20 said crank, a rock lever pivotally mounted in said plane and connected to said crank, rods connected to said rock lever and extending laterally therefrom, wheels connected to said rods, means normally engaged with said crank but movable 25 by the control lines to disengage the crank whereby said crank rotating means moves said crank to raise and lower said wheels.

4. A landing gear mechanism for toy airplanes operable by control lines, comprising, a crank shaft rotatably mounted in said plane, means connected thereto tending to rotate said crank, a stop rest pivotally mounted adjacent said crank and normally engaged therewith, said control lines being operatively connected to said stop rest, a pivot plate linked with said crank, wheel assemblies connected to said pivot plate, wheels connected to said wheel assemblies, said stop rest being movable by the control lines to disengage said rest from said crank so that the crank rotating means moves said crank through 180° and re-engages said rest, the rotation of said 30 crank moving said pivot plate whereby said wheel assemblies are moved to raise and lower said wheels.

5. In a toy airplane, a landing gear mechanism operable to raise and lower the wheels, including control lines leading from the ground to the plane and normally employed to control the flight thereof, a crank, means to rotate said 40 crank, a pivotally mounted stop rest normally engaged with said crank, wheel assemblies linked to said crank, wheels supported thereon, said control lines being operatively connected to said stop rest to disengage it from the crank whereby said 45 crank rotating means rotates said crank to move said wheel assemblies to raise and lower said wheels.
